UNITED STATES PATENT OFFICE.

JOHN CAMERON, OF NEWARK, NEW JERSEY.

DAVIT.

1,162,132.

Specification of Letters Patent.

Patented Nov. 30, 1915.

Application filed June 7, 1915. Serial No. 32,530.

To all whom it may concern:

Be it known that I, JOHN CAMERON, a citizen of the United States, and a resident of Newark, county of Essex, and State of New Jersey, have invented certain new and useful Improvements in Davits, of which the following is a specification.

This invention relates to an improved davit for suspending and also for launching life boats or similar small craft from vessels, wharves and like places on which such small craft are used or stowed. The invention provides a davit for this purpose, which davit is steady when it is in the position it occupies when suspending a boat inboard, being provided with means for holding the arms of the davit against swinging.

The davit is one which has a tripping means for releasing the holding means of the arms so that the arms can be swung in the usual manner to place the life boat or other small craft outboard, the holding means becoming automatically operative when the arms are in their outboard position, so that the arms, and consequently the boat, are held steady against swinging due to any pitching of the vessel on which the davit is mounted. The holding means is preferably so mounted that any pitching of the vessel and consequent fore and aft swinging of the life boat serves to assure the locking of said holding means.

The davit is designed to provide a means for launching life boats and the like, which davit requires a less number of men to operate it to swing the life boat outward than the old form of davit, the number of men employed at the task of preventing undue swinging due to pitching being necessarily few, since the swinging of the arms in the operation of swinging the boat outboard is limited, and successive fore and aft movements of the arms operate to automatically lock the arms against further swinging after the arms are both in their outboard positions. The same is true when the arms are swung to their inboard positions.

The davit and its locking mechanism is simple, which insures its operation when needed, and the mechanism is located and disposed so that it is not in the way of passengers or crew when they are to use the boats. The locking or holding mechanism is not bulky and does not occupy much deck space, and the tripping means for releasing the locking mechanism can be conveniently

placed for easy operation, the person after tripping the holding mechanism being available for other duties and labor in swinging the arms of the davit and the boat.

60

It will be understood that minor changes can be made and the relation and disposition of the parts altered from that shown in the drawings without departing from the scope of my invention. The illustrations 65 show one embodiment of my invention for the purpose of clearly setting forth the operation thereof, and is not the only form in which the invention can be produced.

In the drawings, Figure 1 is a face view 70 of my improved davit with the arms broken away near the lower part thereof. Fig. 2 is an end view thereof on a slightly larger scale. Fig. 3 is an enlarged section of one davit arm and its locking mechanism taken 75 on line 3-3 in Fig. 2. Fig. 4 is a front view of the mechanism shown in Fig. 3. Figs. 5, 6, 7 and 8 are diagrammatic views of the davit and arms and locking mechanism showing the successive positions of 80 them when a boat is swung from its inboard position to its outboard position.

In the form shown in the drawings, the davit comprises two arms 10 and 11 which are of any suitable shape, preferably curved 85 at the upper portion to give a proper overhang. The davit arms are mounted in suitable bearings 12 secured to the side or top of the deck 13, the arms being usually extended below the bearings 12 to lower bearings 14 on the next lower deck or at an intermediate point. The arms are held better against tilting when mounted in vertically separated bearings. The arms are provided on their top ends with means for suspending a life boat or similar small craft. One form of suspension means is shown in the drawing, this consisting of frames 15 which are pivoted at 16 to the eyes 17 of the arms 10 and 11. The boat 18 is suspended 95 from the frames in any desired way, the tackle 19 being usually employed.

The davit arms 10 and 11 are preferably connected so that they can be used more in unison than if they were independent and with less strain on the boat and the tackle. The drawings show this connection in the form of a bar 20 swiveled or pivoted at each end as at 21 to the tops of the frames 15.

The arms 10 and 11 of the davit are provided with holding or locking means that normally hold the davits in outboard or in-

board positions, but which are adapted to be tripped or released, and when so released permit the swinging of the arms to a position reverse to the position they were in when tripped. The swinging of the arms causes the holding mechanism to become operative when the arms arrive in the position to which they are expected to be swung. In the form shown in the drawings the arms 10 and 11 are provided with duplicate mechanisms. On the deck 13 are arranged the base plates 22 of any suitable shape, being usually in the form of divided or V-shaped arms as will be seen from Fig. 3, the arms being adapted to be secured by bolting or other means to the deck 13 or other suitable support. Each base plate has a block 23 and a raised part 24, the ends 25 and 26 of which form stops for purposes to be hereinafter described. The davit arms 10 and 11 pass centrally through the blocks 23 and are rotatable therein. The arms 10 and 11 have secured thereto collars 27 usually made in halves and bolted around the arms, the collars having studs 28 on which the sleeves 29 are rotatably arranged, the sleeves being secured to the segmental gears 30 and 31, the gears on the same studs swinging in unison. To the sleeves 29 are also secured the pawls 32 which lie so that their ends, when dropped, will swing to positions abutting on the stops 25 and 26.

On each block 23 are racks 33 and 34 which are preferably placed out of the path of travel of the pawls 32 but are in the path of the segmental gears 30 and 31. In the form shown, each rack 33 is on the inside and is adapted to engage a segmental gear 30, and each rack 34 is on the outer edge of the block 23 and adapted to engage the segmental gear 31. The racks are placed so that they will operate their respective gears to turn over the pawls attached to the gears to cause the pawls to be placed in proper operative positions, as will be described hereinafter. The gears have their teeth extended around their peripheries far enough to permit their engagement with their respective racks when the pawls are swung to one side of their centers, but to cause them to engage their respective racks when the pawls are swung to the other side of the centers.

The disposition of the parts can be changed in various ways and still bring about the desired results, but in the drawing the raised part or abutment 24 on each block 23 is on the outer side of its block, that is, on the side farthest away from the other, and, as clearly shown in Fig. 1, the pawls are in engagement with the edges 26 of the abutments and the davit arms are locked against any swinging movement. It will, of course, be understood that any suitable lashing or tying can be done to secure

the boat 18 from swinging in relation to the davit arms when the boat is stowed, and such means are not shown on the drawing.

Suitable means for tripping the holding means, such as the pawls 32, are provided, these consisting, in the embodiment illustrated, of short levers or noses 35 arranged on both sides of each block 23, the noses or levers being mounted to swing with a shaft 36 mounted in the bearing 37. The noses 35 are placed so that they will be underneath the lugs 38 of the pawls 32. The rocking of the shafts 36 and their noses 35 is limited by suitable means, such as the stops 39, which engage the bearings 37 so that the noses can not be swung too far upward. Suitable handles or levers 40 are provided for the rocking of the shafts 36 and are conveniently placed so that the pawl of the locking mechanism, which is adapted to be operated, can be tripped without inconvenience.

The operation of the device is as follows: Assuming that the boat 18 has been swung inboard, as shown in Fig. 5, the pawls 32 will both be on the near side and engaging the edges 26 of the abutments 24, and the davits can not swing, and the whole structure is in locked or rigid position. When it is desired to swing the boat outboard, either one of the pawls can be operated to initiate the movement, but in the directions shown in Figs. 5 to 8, inclusive, it will be seen that the one to the left is operated first. This operation takes place by a person swinging the handle 40 on this particular side of the davit and raising the pawl 32 through the intermediate mechanism which raises the pawl above the top of the stop 26, and this pawl is swung forward, as will be clearly seen from Fig. 6, causing the other pawl on the right hand side of Fig. 5 to retreat from its stop, the two davit arms working in unison by reason of their being connected by the bar 20, but this connection, it will be understood, is not unduly strained, if the distance between the ends of the tops of the davit arms becomes slightly greater or less than normal due to the unequal swinging of them, by reason of the frames 15 to which the bar 20 is fastened being pivoted to the tops of the arms as at 16. When the pawl 32 on the right in Fig. 6 retreats it does not turn over because in this position the segmental gear 31 has its bottommost tooth, as at *a* in Fig. 4, above the line of teeth in the rack 34. It will be understood that in the movement so far as illustrated in Fig. 6, the pawl 32 slides without obstruction along the block 23. The davit arm 11 is now swung as indicated in dotted lines at *b*, and when this swinging takes place, the davit arm 10 is necessarily swung to a position farther around toward the outside, as shown in dotted out-

line in Fig. 6. When the davit arm 11 swings outward, and as it approaches the position which it is shown in in Fig. 7, the segmental gear 30 engages the teeth of the rack 33, and since the teeth on the gear 30 are out of line circumferentially with the teeth of the gear 31, the segmental gear 30 engages the rack 33, and the gear and the pawl being cleared, the pawl is caused, by gravity, to fall in a position reverse to the one in which it was started, but it falls with its end beyond the stop or edge 25 of the abutment 24 and is thus not halted in its swinging movement. The davit arm 10 is now swung outboard, as indicated by the dotted line *c* in Fig. 7, which causes the davit arm 11 to be swung to the dotted position shown in Fig. 7, but as the davit arm 10 is swung outboard, the davit arm 11 is also brought around again to an outboard position, and the davit arm 10 in being swung outboard—*i. e.* from the position shown in Fig. 6 to that shown in Fig. 7—has its pawl 32 turned over as in the case of the davit arm 11 when it was swung outboard. The movement of the davit arm 10 to its outboard position has necessitated the retreating or pulling back of the pawl 32 of the davit arm 11 until it is in rear of its stop 25, and a swinging movement slightly to the right will bring it to the position shown in Fig. 8, which, at the same time, permits the bringing of the pawl 32 of the davit arm 10 into position, and the two davit arms are locked in their outboard positions.

It will be evident that when both arms have been swung to a position outward beyond the plane of the pivots of the davit arms that any alternate movement back and forth of the davit arms, due to pitching of the vessel, will assist in operating the locking device so that they automatically will turn over the pawls on the two davit arms, and on a second movement in this direction will insure the locking of these pawls against the stops 25 on the outside of the abutments.

In the old style of davit it was necessary to hold the davit arms against undue swinging due to the pitching of the boat until the guys were made fast, this requiring the services of members of the crew or others. This was difficult, especially on wet decks, and in the event of failure to hold the boats against such swinging it has caused the smashing of boats or enough disarrangement of the gear or tackle to seriously interfere with the launching of the boat. By my improved invention the pitching can in fact be utilized in assisting the locking of the davit arms against swinging or rotation, since swinging in one direction and another swinging in the opposite direction are all that is necessary to turn over both pawls, and as each

one retreats behind its respective stop 25 it will thus be held against successive movement in that direction.

It will be understood that other means for turning the pawls over beside racks and segmental gears can be employed, and the particular form and relation of the parts can be altered without departing from the invention. It will be evident also that in this device there is very little mechanism, and what there is is raised to a slight distance above the deck. It does not, therefore, interfere seriously with the loading of passengers or crew into the boat. After it has been swung outboard, and the lack of obstruction is calculated to go a great way toward speedy loading of boats and thus provide greater safety in emergencies, it requires but little labor to operate the davit, and the absence of the necessity of holding the davit arms against swinging when they are in their outboard positions permits the use of members of the crew, who would be engaged in steadyng the davit arms with the old style of davit, in other directions where they probably would be essential in an emergency.

The parts of this invention are simple in their construction and their functions are simple, thus insuring their operation when required, and particularly in emergencies where there is very apt to be confusion and a lack of order.

Having now described my invention, I claim:

1. A davit comprising rotatably arranged davit arms, and automatic means for locking said arms when both arms are in predetermined positions.

2. A davit comprising rotatably arranged davit arms, automatically operated means on said arms for locking them when both arms are in predetermined positions, and means for tripping said locking means.

3. A davit comprising vertically arranged rotatable davit arms, supporting means for said arms, locking means on the arms for engaging the supporting means to lock the arms in predetermined positions, and means on said support to engage the locking means to automatically cause the locking means to assume a locking position.

4. A davit comprising vertically arranged rotatable davit arms, supporting means for said arms, locking means on the arms for engaging the supporting means to lock the arms in predetermined positions, means on said support to engage the locking means to automatically cause the locking means to assume a locking position, and a tripping means for releasing the locking means.

5. A davit comprising rotatably arranged davit arms, locking means disposed so that the arms are locked only when they are both in their inboard and outboard positions, and

means for causing the automatic operation of said locking means by the rotation of the davit arms.

6. A davit comprising rotatably arranged 5 davit arms, locking means on each arm disposed so that the arms are locked when both have arrived at their inboard and outboard positions, means for causing the automatic operation of said locking means by the rotation of the davit arms, and means for tripping the locking means of one arm which releases both arms for rotation.

7. A davit comprising rotatably arranged davit arms, stops adjacent to said arms, 15 pawls on the arms for engaging the stops only when both arms are in inboard or outboard positions, and means for raising the pawls from the stops.

8. A davit comprising rotatably arranged 20 davit arms, oppositely arranged stops adjacent to each arm, a pawl secured to the arm and adapted to be reversed to alternately engage the stops, and means for engaging the pawl when an arm is rotated, 25 said means acting to reverse the pawl.

9. A davit comprising rotatably arranged davit arms, oppositely arranged stops adjacent to each arm, a pawl secured to the arm and adapted to be reversed to alternately engage the stops, means for engaging the pawl when an arm is rotated, said means acting to reverse the pawl, and a manually 30 operated device for raising a pawl when it is engaging a stop.

35 10. A davit comprising rotatably arranged davit arms, each davit arm having a pivoted pawl thereon, oppositely arranged stops adjacent to each davit arm, the pawl being adapted to be reversed to engage the stops alternately, and reversing means for throwing 40 the pawl when the davit is swung.

11. A davit comprising rotatably arranged davit arms, each davit arm having a pivoted pawl thereon, oppositely arranged stops 45 adjacent to each davit arm, the pawl being

adapted to be reversed to engage the stops alternately, and means for reversing the pawl when the davit is swung, said means being disposed so that the pawl is dropped beyond the stop it is approaching and engages the stop by a slight backward movement of the arm.

12. A davit comprising rotatable arms connected to move substantially in unison, and locking means on each arm to automatically lock the arms in inboard and outboard positions.

13. A davit comprising rotatable arms connected to move substantially in unison, pawls on the arms, stops adjacent to the 60 arms, and means for reversing the pawls when the arms are swung.

14. A davit comprising a rotatable davit arm, a pawl on said arm, oppositely arranged stops, a swinging pawl on the davit 65 to engage the stops from opposite directions, and reversing means in the path of the pawl to reverse the pawl when the arm is swung.

15. A davit comprising a rotatable davit arm, a pawl on said arm, oppositely arranged stops, a swinging pawl on the davit to engage the stops from opposite directions, segmental gears on the pawl, racks in the path of the gears, the gears being disposed so that they will engage their respective 75 racks when the pawl is in predetermined positions in order to reverse the pawl when the davit is swung.

16. A davit comprising a rotatable davit arm, a pawl on said arm, oppositely arranged stops, a swinging pawl on the davit to engage the stops from opposite directions, reversing means in the path of the pawl to reverse the pawl when the arm is swung, and a manually operated means adapted to 85 engage the pawl on each side of the stops.

In testimony that I claim the foregoing, I have hereunto set my hand, this 3rd day of June 1915.

JOHN CAMERON.
